HIGH SPLICE STRUCTURE FOR FULL-FASHIONED STOCKINGS AND METHOD OF MAKING THE SAME

William Nebel, Charlotte, N. C.

Application December 24, 1947, Serial No. 793,617

4 Claims. (Cl. 66—182)

1

This invention relates to a full-fashioned stocking of the single unit type having a leg portion, a high spliced portion, a heel portion and a foot portion and forming the high spliced portion by widening during the formation of the high spliced portion and preferably forming the widening marks within two to four wales of the selvedge wale of the stocking so that the widening marks will be hidden in a seaming operation, widening the heel portion which merges with the high spliced portion, then knitting a plurality of courses at the middle of the heel pocket and then narrowing in the lower heel portion to produce a perfectly fitting single unit stocking which has a much better fit and less strain on the loops than other single unit stockings heretofore produced.

It is also an object of this invention to provide a stocking having leg narrowings extending to the vicinity of the top edge of a high spliced portion and then when the high spliced portion is begun or immediately after it is begun, the high spliced portion is widened by forming the widening loops adjacent the selvedge edge so that these widening loops will be hidden in a seaming operation and after the high splice portion has been knitted, then knitting the remainder of the stocking blank in a conventional manner.

Some of the objects of the invention having been stated, other objects will appear as the description proceeds when taken in connection with the accompanying drawings, in which

Figure 1 is a side elevation of a stocking made in accordance with my invention;

Figure 2 is a rear view looking from the right-hand side of Figure 1;

Figure 3 is a view of the lower portion of the stocking blank employing my invention;

Figure 4 is a schematic view of the upper right-hand corner of Figure 3;

Figure 5 is a view similar to Figure 3 but omitting the leg narrowings immediately above the high spliced portion.

Referring more specifically to the drawings, the numeral 10 indicates the lower leg portion of a stocking. As is well known, in the knitting of a single unit stocking, the welt portion is first knitted and then the main leg portion and as the leg portion approaches the foot portion suitable calf or lower leg narrowings are employed for reducing the size of the stocking to fit the leg of the wearer. Sometimes these narrowing marks stop substantially short of the high splice of a ladies stocking in order to produce what is known as a large ankle, but in Figure 3 there is

2

a plurality of narrowing marks 11 disposed adjacent the selvedge of the blank preferably three or four wales from the selvedge loops so as to be hidden by a seaming operation. These narrowings are usually two needles narrowings at each edge and then seven courses are knitted and narrowing with another two needles at each edge takes place and then another seven courses are knitted, and this is repeated a plurality of times until the blank has reached the point where the reinforcement can be thrown in to make the high splice.

In the preferred embodiment of the invention, these narrowings in the leg portions are indicated 15 in Figure 4 by reference character 12 to produce the narrowing marks 11, and when the point 13 is reached the high splice H is commenced and is continued without widening or narrowing for approximately eight courses as at 14 and the reinforcing thread is knitted along with the body 20 thread. After about eight courses have been knitted, widening out of approximately two needles on each side of the blank occurs as at 15 and approximately ten courses are knitted as 25 at 16. Then widening out two needles at each edge of the blank occurs at 17 and another ten courses are knitted as at 18. When these ten courses are knitted, then widening out takes place as at 20 and approximately twelve courses are 30 knitted as at 21 without either widening or narrowing.

When these twelve courses have been knitted, then widening occurs as at 22 and approximately eighteen courses are knitted without widening or narrowing. After these eighteen courses have 35 been knitted, the top of the heel pocket P is begun and widening again occurs at two needles on each edge of the blank and four courses are knitted and this is repeated as at 24, 25, 26, 27, 28, 29, 30, 31, 32, 33, 34, 35, 36, 37, 38 and 39 and continued until approximately twenty-one of the 40 widening courses indicated at 24 to 39 have been completed. When the heel pocket is begun, the reinforcing thread is extending further inwardly in steps as to 41 to present an ornamental effect and to give better wear.

At this point indicated at 40, approximately forty courses are knitted as at 43 without either widening or narrowing. Then beginning at point 44, the lower heel narrowings are begun by narrowing two needles at the selvedge edge of the blank at each narrowing operation throughout the line of narrowing marks indicated at 45, the first three steps of narrowing having five courses 45 between the narrowings and then three more 50 between the narrowings and then three more

steps of narrowings having four courses between the narrowings and three more steps of narrowings having three courses between the narrowings and then six narrowing steps having two courses between the narrowings and then three different narrowings having three courses between the sets of narrowings are knitted, and then three more steps of narrowings each having four courses between the steps of narrowings and then three other steps of narrowings having five courses between the steps of narrowings at which point indicated at 46, the narrowings in the lower heel have been completed and the rest of the foot is knitted to where the toe narrowings 47 occur without either widening or narrowing.

It is to be noted that throughout the high spliced portion, the proximate edges of the high spliced reinforcement in the blank and indicated at 48 in Figure 3 stop on an identical wale so as to present a refined appearance to the outer edges of the high splice in the finished stocking the high splice as shown in Figures 1 and 2.

It is thus seen that I have provided a single unit full-fashioned stocking having leg narrowings extending to the top of the high spliced portion and then having the widening immediately occur and progress throughout the high spliced portion with the widening marks being preferably disposed adjacent the selvedge edge so that the widening marks will be hidden in a seaming operation and said high spliced portion merging with the upper portion of the heel pocket which may have its widening marks within a few wales of the selvedge edge so that these widening marks in the upper heel pocket will likewise be hidden in a seaming operation. The stocking also has narrowings in the lower part of the heel which may be adjacent the selvedge wales so that these narrowing marks will also be covered in a seaming operation.

In Figure 5 a slightly modified form of the invention is shown which is identical to the structure previously described with relation to Figures 1 to 4 with the exception that the lower leg portion or ankle portion adjacent the top end of the high spliced portion does not have any narrowings whatever, thus providing what is known as a wide ankle stocking, but the high spliced portion and the upper heel portion and the lower heel portion are knitted exactly as previously described with relation to Figures 1 to 4 inclusive.

It might be noted that after substantially all of the high spliced portion of the heel blanks have been knitted, the reinforcing yarn is extended inwardly toward the middle of the blank of the stocking in stepped relation as indicated at 49 to thus provide an ornamental effect to the heel portion.

In the drawings and specification while I have described specifically the numbers of narrowings and widenings, the numbers of needles narrowed and the number of courses between narrowings or widenings, it is specifically understood that I am not limited to such numbers of needles or courses between the narrowings and widenings, but that any approximate numbers would fall within the scope of the invention as it is evident that where four courses are knitted between the narrowings or widenings, that this could be three or five courses or any reasonable variation thereof.

In the drawings and specification there has been set forth a preferred embodiment of the

invention, and although specific terms are employed, they are used in a generic and descriptive sense only and not for purposes of limitation, the scope of the invention being defined in the claims.

I claim:

1. In a single unit blank for a full-fashioned stocking having an ankle portion and heel portions and a leg portion with leg narrowings therein adjacent the selvedge edges and disposed immediately above the ankle portion, said blank having ankle widenings extending downwardly along the selvedge edges from the point where the leg narrowings stop, high spliced portions beginning at the point of widening along each edge of the blank and having the edge of each of the high spliced portions in the blank remote from the selvedge edge occurring in a continuous wale and the reinforcing thread forming the high spliced portions extending outwardly in each widening operation to provide high spliced portions having narrow upper portions and gradually widening lower portions merging into the upper heel portions.

2. That method of knitting a single unit full-fashioned stocking blank which comprises narrowing the blank at the lower end of the leg portion as it approaches the ankle portion, then widening the blank at the selvedge edges until the upper heel portions are reached, and at the same time feeding splicing yarn to a plurality of the outermost needles at each edge of the blank during the widening operation with the splicing yarn stopping in spaced parallel wales remote from the selvedge edges of the blank, and forming all of the widening and narrowing marks within two or three wales from the edge of the blank so that the narrowing and widening marks will be hidden in a seaming operation to complete the stocking.

3. In a blank for a full-fashioned stocking having a leg portion with leg narrowings therein immediately above the ankle portion and having ankle widenings along the selvedge edges and extending downwardly from the point where the leg narrowings stop, high spliced portions beginning at the point of starting of the ankle widenings and having the proximate edges of the high spliced portions in the blank occurring in two parallel wales, and the reinforcing thread forming the two high spliced portions extending outwardly in each widening operation to provide high spliced portions each having a narrow upper portion and a gradually widening lower portion.

4. That method of knitting a full-fashioned stocking blank which comprises narrowing at the lower end of the leg portion as it approaches the ankle portion, then widening by placing the widening marks near the selvedge edges until the upper heel portions are reached and at the same time feeding splicing yarns to the needles along the outer edges of the blank during the widening operation with the inner edge of the widening yarn for each high spliced portion stopping in a continuous wale, and forming all of the widening and narrowing marks within two or three wales from the edge of the blank so that the narrowing and widening marks will be hidden in a seaming operation to complete the stocking.
